UNITED STATES PATENT OFFICE.

LESLIE D. RICKER, OF GRAND JUNCTION, COLORADO.

COOKER.

Application filed September 19, 1919. Serial No. 324,842.

To all whom it may concern:

Be it known that I, LESLIE D. RICKER, a citizen of the United States, residing at Grand Junction, in the county of Mesa and 5 State of Colorado, have invented new and useful Improvements in Cookers, of which the following is a specification.

This invention relates to a cooker, and one object is to provide an apparatus by the 10 use of which many kinds of food may be prepared at one time, in the manner best suited to the particular articles, provision being made for a large number of persons.

A further object is to provide for cooking 15 by dry heat and by steam in the same apparatus and at the same time.

A still further object is to provide an apparatus which shall include a heat insulated casing, a heating element, a lower oven, a 20 boiler of special construction above the oven and designed for receiving several articles at one time, an upper oven and a live steam cooker on the upper portion of the device, also adapted to receive a number of different 25 articles in separate compartments.

With the foregoing and other objects in view, the invention consists in the novel construction, combination and arrangement of elements hereinafter described and claimed.

30 In the drawings,

Figure 1 is a view in vertical section,

Figure 2 is a vertical section from another angle, with plate 35 omitted.

Figure 3 is a transverse section.

35 Figure 4 is a detail, in elevation, of a device for elevating the receptacles from the casing.

Figure 5 is a detail in vertical section of the upper portion of the casing, with the 40 shelves and double boiler removed.

Figure 6 is a detail of a hinged sill used between the doors.

Figure 7 shows a water gage for the double boiler.

45 Figure 8 is a top plan view of one of the plates 68 of the upper chamber, the view showing the annular space 67 around the plate, to permit of the passage of steam emerging from perforated tube 77.

50 The outer casing or shell is shown at 10 and is preferably of sheet steel, an inner wall for the casing being designated 14, and a heat insulating packing being shown at 12. Within the lower portion of the shell

or casing thus formed is a fire-box, the double walls of which are formed of hard fire clay, the walls being designated 15 and 16.

Within the fire box is a burner 17 having connection with the supply pipe, 18, a cut off valve being shown at 19. A coil 20 within the fire-box is adapted for connection with a source of water supply.

The walls 22 are spaced from the walls 12 and 14 of the casing proper, and provide flues 23 having communication at their lower 65 ends 24 with the fire-box. Lower dampers 25 control the openings to the flues, and upper dampers 26 are located as shown and are under the control of operating devices 27, similar operating devices being shown in 70 connection with dampers 25.

The lower oven 28 is provided with shelves 29 which may be of tile, these shelves being retained upon supports 30, permitting the shelves to be shifted from one location to 75 another, or permitting certain of them to be withdrawn, if desired. A lower heat absorbing tile 31 is mounted on supporting ribs or flanges 32 and above the fire box. This tile 31 is provided with a plurality of 80 apertures which may be closed by plugs 33, the plugs being removable, when it is desired to permit the heat units to pass thru the tiles to the oven. A plate 35 of non-conducting material may be placed above the tile 85 31 when it is desired to modify the temperature by the use of this device. A similar plate 36 of non-conducting material may be used below the upper oven, to be described below.

Above the oven 28 is a boiler 40 of special construction and comprising a plurality of 90 separate compartments, if desired, in order that various articles of food may be cooked at one time therein. This device is of the 95 double boiler type. Inlet and outlet pipes are detachable and are connected with the outer fluid compartment of the boiler as shown at 42 and 43. The boiler as a whole is mounted on wheels 44 operating on tracks 100 45 permitting of the removal of the boiler by withdrawing the latter laterally from the apparatus, any suitable supporting means exterior of the apparatus being provided.

The upper oven 47 is supplied with shelves 105 48, retained in position by supporting devices 49, similar to those employed by the lower oven. The packing material before

referred to as being located between the inner and outer walls of the main casing extends over the top of the upper oven.

The walls of the main casing are provided 5 with a plurality of doors each swinging on a vertical axis and having bevelled edges, in order to provide a substantially air tight fit. Swinging sills 50 are located as shown and permit unobstructed access to the interior.

The live steam cooker at the top of the apparatus includes a base 55 provided with flanges 56 projecting upwardly therefrom, and flanges 57, spaced as indicated and provided with gaskets 58, receiving the walls 59 and 59' of the upper structure 60 constituting the housing of the live steam cooker. This structure 60 is divided into a plurality of compartments 61 in which are 15 located racks or casings 62 for the reception of food to be cooked. The casings are removable and are formed with sheet metal walls 63 and a perforated metal top 64. The lower portion of the casings are open for the admission of steam. The doors are designated 65.

Between the flanged portions 56 of the base, and the openings provided between these flanges, are plates 68 providing an annular space 67 around the plates 68, thru which steam passes to the compartments for heating the food, passing thence through the shelves 69 of wire mesh and out thru openings in the top closed by means of 35 valves 70. These are spring held valves and are adjusted to operate under a pressure slightly less than the steam pressure employed. The steam passes thence into the space between the walls 59 and 59'. The 40 water of condensation may be conveyed in any suitable manner to the separator 73. The main steam inlet pipe for the steam cooking device is designated at 74, and the branches 75 conduct steam to the connection 76 and 45 thence thru the perforated tubes 77, the steam passing into chambers 78 and thru annular openings 67, into the cooking compartments. Plates 68 are mounted on the perforated tube just mentioned.

50 A smoke flue 80 is closed by a weighted cover 81 and permits of the escape of products of combustion, the weighted portion being sufficient to permit the cover to open under very slight pressure and to close automatically. Hooks 83 and 84 are provided respectively on the upper structure and on the main casing or shell and links 85 engaging the hooks are under the control of cam levers 86, permitting the walls of the upper structure to be pressed down tightly on the gaskets before mentioned in order to effect a substantially steam tight connection.

An upper frame work comprises vertical supports 90 and a transverse element or elements 91 mounting pulleys 92 over which

flexible devices pass from the counterbalancing weights 93 and 94, one end of each flexible device being connected with a ring member or hook 95 on the upper casing.

Any inconvenience arising from the 70 weight of the steam cooker proper is thereby avoided, and it should be added that the cooker last named may be removed from the balance of the apparatus when space or other conditions render such course desirable.

Any inconvenience arising from the 70 weight of the steam cooker proper is thereby avoided, and it should be added that the cooker last named may be removed from the balance of the apparatus when space or other conditions render such course desirable.

A crane 98 mounts pulleys 99 and accommodates a small cable or other flexible device connecting with a winding apparatus 100. The cable is provided with a hook 101 80 at its free end, this apparatus being used for any purpose desired, such as removing the entire double boiler 40 with its contents, it being understood that the apparatus may be of sufficient capacity to supply a large number of individuals. The double boiler can be kept hot when removed by means of circulation thru pipes 42 and 43, the circulating fluid being provided by any suitable source. When this boiler is removed all of 90 the space between the fire box and the upper wall of the main casing may be utilized as an oven. In Figure 5 a series of hooks 103 is shown for use in suspending articles being cooked, or receptacles containing those articles.

95 A bracket 105 on the outer portion of the casing will serve to support a motor, and a bushing 106 is provided in the wall of the casing for the accommodation of a shaft 107. This shaft 107 is for use in driving a flexible 100 shaft for operating stirring devices for the double boiler, in the event such devices are employed. They do not form a part of the invention covered by the present application. 105

It will be observed that different temperatures may be maintained at the same time in various portions of the cooking device, thereby making it possible to cook a large variety of articles of food. The lower oven is designed for roasting, frying, broiling and the like, and it may be remarked that the tile shelving may be more quickly heated by placing the individual shelves directly over the lower tile 31, the plugs 33 being removed 110 if desired. Pans for baking or frying may be supported directly on the inwardly projecting guide or supporting devices 30, and an article of food may be fried on one side of the given tile after the latter has been heated and placed in position, and another article may be broiled on the other side of the tile or below the latter. The various food containers in the boiler 40 and in the steam cooking apparatus may be removed separately if desired, suitable devices for handling these elements being provided, and the containers may be filled or emptied after they have been withdrawn and placed 115 on a table or in any suitable position.

tion. A water guage 110 is employed in connection with the double boiler 40, and means for indicating the temperature in the various compartments of the entire apparatus may 5 be of course provided.

What I claim is—

1. In a cooker, a casing comprising inner and outer walls and insulating material therebetween, a fire-box in the lower portion 10 of the casing, a heating element therein, an oven located above the fire-box, a cooking utensil above the oven, a cooking device located above the casing and including a plurality of compartments, a chamber being 15 provided below said compartments, a heating coil within the fire-box, and a pipe for conducting steam from the coil into the plurality of compartments through the chamber below the compartments.
2. In a cooker, a heat insulated casing, a fire-box in the lower portion thereof, a heating element within the fire-box, a chamber within the casing and having walls spaced from the walls of the casing, means 20 for effecting and cutting off communication between the space and the fire-box, an independent cooking apparatus within the middle portion of the casing, for receiving articles to be cooked in water, an oven with- 25 in the upper portion of the casing, an additional cooking apparatus above the casing, and means for supplying steam thereto from the heating element in said fire-box.
3. In a cooker, a main casing having heat 30 insulated walls provided with openings in the sides thereof, closures for said openings, hinged sills between the openings, an inner chamber having walls spaced from the walls of the casing, cooking compartments within 35 the chamber, one of which is removable through the openings in the walls, and means for conducting a heating fluid to the compartment last named.
4. In a cooker, a main casing having heat 40 insulated walls, a chamber within said cas-

ing and having walls spaced from the walls of the casing providing flues, a fire-box communicating with the flues, draft regulating means for the flues, an oven within the chamber, a heat absorbing element provided with apertures forming the bottom of the oven, means for closing the apertures, said means being removable, and a separate element of non-conducting material adapted to be placed above the heat absorbing element when it is desired to modify the temperature. 50

5. In a device of the class described, a main casing and means for heating the interior thereof, an independent cooking apparatus on the upper portion of the main casing and including a plurality of separate compartments each provided with a steam inlet, perforated tubular members having communication with the inlets, a 60 plate member mounted on each tubular member, the bottom of each compartment having an opening the edges of which are spaced from the edge of the plate for the admission of steam to the compartment, and 65 pressure controlled means governing the escape of steam from the compartment. 70

6. A cooker comprising a base having upwardly extending flanges thereon, a removable casing mounted on the base and includ- 75 ing separate compartments having walls spaced from the walls of the casing and the top of each compartment being spaced from the top of the casing, means for admitting steam to each compartment separately and 80 controlling its passage therethrough to the space between the walls, said walls being in contact with the flanges of the base, said means for admitting steam including a circular plate and a member surrounding the 85 plate and spaced therefrom to provide an annular discharge opening.

In testimony whereof I affix my signature.

LESLIE D. RICKER.
